REFRIGERATION

Harry K. Bergholm, Stockholm, Sweden, assignor, by mesne assignments, to Servel, Inc., Dover, Del., a corporation of Delaware

Application April 16, 1935, Serial No. 16,555
In Germany April 19, 1934

3 Claims. (Cl. 62—119.5)

My invention relates to refrigeration and more particularly to a refrigeration system of the absorption type in which refrigerant evaporates and diffuses into an auxiliary fluid.

5 It is an object of the invention to provide an improved system of this type which produces refrigeration at a plurality of temperatures and at increased efficiency.

My invention, together with the objects and 10 advantages thereof, will become apparent upon consideration of the following description and the accompanying drawings forming a part of this specification, and of which:

Fig. 1 shows in vertical section a refrigerator 15 embodying my invention; and

Fig. 2 is a rear view of the refrigerating unit appearing in side elevation in Fig. 1.

Referring to the drawings, a refrigeration system comprises a generator 10 interconnected through a liquid heat exchanger 11 with an air cooled absorber comprising an air cooled coil 12 and a tank 12' for circulation therebetween of absorption liquid. The upper part of the generator 10 is connected by a conduit 13 to a first 20 part 14 of an air cooled condenser. Conduit 13 extends upwardly through a rectifier vessel 15 to the upper part of which is connected the lower end of the first part 14 of the condenser. The upper part of the rectifier vessel 15 is also connected to the upper end of a second part 16 of the 25 air cooled condenser.

Within a thermally insulated storage compartment 17 of a refrigerator cabinet is a cooling element including a high temperature section 18 and 30 a low temperature section 19. The high temperature section 18 is located uppermost and comprises a closed tube provided with external heat transfer fins 20. Within the high temperature section 18 is a plurality of baffles 21 comprising 35 disc partitions having relatively large central openings. The lower part of the baffles 21 forms weirs along the bottom of the high temperature evaporator section 18 in the path of flow of liquid 40 therein, as will hereinafter appear.

45 The low temperature evaporator section 19 is formed by a pipe coil arranged for continuously downward flow of liquid therein. This coil may be imbedded in or otherwise arranged in thermal transfer relation with a suitable ice tray receptacle or the like 22 which may be an aluminum 50 casting.

The rear end of the high temperature evaporator 18, which is slightly lower than the forward end, is connected by means of a conduit 23 55 to the upper end of the pipe coil 19. The pipe coil

19 is interconnected through a gas heat exchanger 24 with the absorber 12 for circulation therebetween of an auxiliary fluid. The lower end of the pipe coil 19 may be connected directly to the gas heat exchanger 24 and the upper end of the pipe coil is connected to the heat exchanger by means of a conduit 25.

The gas heat exchanger 24 is of a known type comprising an outer tubular shell divided into a long central chamber and relatively small end 10 chambers by partitions 26. The two end chambers 27 and 28 are connected by a plurality of tubes 29 which extend through the middle chamber 30. The forward end of the high temperature evaporator section 18 is connected to the 15 central chamber 30 of the gas heat exchanger 24 by means of a conduit 31. This conduit extends centrally through the high temperature section 18 and terminates in the forward end thereof preferably with a slightly upturned end 32. The 20 rear end of the high temperature evaporator section 18 is also connected to the central chamber 30 of the gas heat exchanger by means of a conduit 33.

The rectifier vessel 15 is connected by means of 25 a conduit 34 to an intermediate point 35 of the low temperature evaporator coil 19. A vent conduit 36, including a pressure vessel 37, is connected between the lower end of the condenser section 16 and the gas heat exchanger 24.

The refrigeration system is charged with a solution of refrigerant in an absorption liquid, such as a 30% water solution of ammonia. This may be introduced into the system through a charging plug (not shown) in the absorber 12. An auxiliary fluid, as, for instance, hydrogen, is introduced into the system under a pressure corresponding to that at which ammonia will condense, for instance, a fairly high room temperature. The generator 10 is heated in any desired manner 40 as, for instance, by a gas burner 38.

In operation, ammonia vapor is expelled from solution by heat in the generator 10. The ammonia vapor flows through conduit 13 to the first part 14 of the condenser. Liquid ammonia 45 formed in the part 14 of the condenser flows into the rectifier vessel 15 and thence through conduit 34 into the lower portion of the evaporator coil 19. Ammonia vapor flows from the upper part of the rectifier 15 to the second part 50 16 of the condenser. Liquid ammonia formed in the part 16 of the condenser flows through conduit 9 into the forward end of the high temperature evaporator section 18. In the latter the liquid ammonia flows over the internal baffles 21 55

to the rear end of this section and thence through conduit 23 into the upper end of the low temperature evaporator coil 19.

Hydrogen enters the upper end of the evaporator coil 19 through conduit 25. In the coil 19, liquid ammonia evaporates and diffuses into the hydrogen producing a refrigerating effect. The resulting gas mixture, being heavier than the hydrogen, flows downwardly in coil 19 and 10 thence through the chamber 30 of the gas heat exchanger 24 and conduit 39 to the absorber tank 12'. In the absorber, ammonia is absorbed out of the gas mixture by weak absorption solution and the hydrogen or weak gas flows 15 through conduit 40, internal tubes 29 of the gas heat exchanger 24 and conduit 25 back to the upper end of the evaporator coil 19.

Circulation of absorption liquid between the generator 10 and absorber is accomplished by 20 means of a thermosyphon conduit 41 arranged to be heated by the gas burner 38. By means of the thermosyphon conduit 41, liquid is raised to such a level in the generator 10 that it may flow by gravity from the lower part thereof 25 through conduit 42, the liquid heat exchanger 11 and conduit 43 into the upper part of the absorber. Enriched absorption liquid formed in the absorber flows from the lower part of the absorber tank 12' through conduit 44, the liquid 30 heat exchanger 11 and the thermosyphon conduit 41 back to the upper part of the generator 10.

Since conduits 31 and 33 are connected to the chamber 30 of the gas heat exchanger 24, hydrogen is conducted into the high temperature evaporator section 18. Liquid ammonia in this evaporator section evaporates and diffuses into the hydrogen producing a refrigerating effect. The resulting gas mixture, thus becoming 40 heavier, descends through conduit 33 back into the central gas heat exchanger chamber 30 and flows therefrom through conduit 39 to the absorber 12. Since the gas heat exchanger chamber 30 contains rich gas from the evaporator 45 coil 19, some of this rich gas is conducted upwardly through conduit 31 into the high temperature evaporator section 18 to replace that which leaves through conduit 33. Thus is created a local circulation of rich gas from the 50 evaporator coil 19 through the high temperature evaporator section 18. In the evaporator section 18, the partial pressure of ammonia in the gas which enters this section through conduit 31 determines the temperature at which ammonia evaporates in this section. Since the 55 partial pressure of ammonia in the hydrogen in the evaporator section 18 is higher than the partial pressure of ammonia in the hydrogen entering the evaporator coil 19, the temperature 60 of the evaporator section 18 will be higher than the temperature of the evaporator coil 19. The liquid ammonia which flows through conduit 23 from the evaporator section 18 to the evaporator coil 19 has become cooled, due to evaporation in 65 the section 18, to a temperature lower than that at which it comes from the condenser portion 16. Therefore, the evaporator coil 19 may be maintained at a lower temperature than that if liquid ammonia were conducted directly there- 70 to from the condenser.

Air in the refrigerator compartment 17 may be cooled by flowing first in thermal exchange relation with the high temperature section 18 and then with the low temperature section 75 formed by the coil 19 and tray receptacle 22.

The latter or low temperature section has a relatively limited surface for contact with the air, this surface merely being sufficient for maintaining the air at the desired temperature when heat leakage into the refrigerator compartment as determined by the outside or room temperature is low. Under these conditions, that is, low air temperature, the surface of the first condenser section 14 will be sufficient to produce condensation of all the ammonia so 10 that liquid ammonia will be delivered only to the evaporator coil 19 through conduit 34. However, upon increase in air temperature, unevaporated ammonia is supplied to the second condenser 15 section 16 and liquid ammonia from this condenser section flows through conduit 9 into the high temperature evaporator section 18, thus bringing the more extensive surface of this evaporator section into effect for cooling the air in the refrigerator compartment 17. At this 20 time, this additional air cooling surface is necessary because heat leakage into the box has increased.

It will be understood that various changes and modifications may be made within the scope of 25 my invention embodied in the herein described refrigerator.

What is claimed is:

1. In a refrigerator, a thermally insulated refrigerating compartment, and a refrigeration apparatus including a first evaporator section having extensive heat transfer surface, a second evaporator section having a relatively limited heat transfer surface, a generator, an absorber, means for circulating absorption liquid between 30 said generator and absorber, a first condenser, a second condenser, means for conducting refrigerant vapor from said generator to said first condenser, means for conducting liquid from said first condenser to said second evaporator section, means for conducting vapor from said first condenser to said second condenser, means for conducting liquid from said second condenser to said first evaporator section, means for conducting 35 unevaporated liquid from said first evaporator section to said second evaporator section, and means to conduct auxiliary gas in a circuit including said absorber and said second evaporator section and including means for conducting a portion of the gas flowing from said second 40 evaporator section to said absorber through said first evaporator section.

2. In a refrigerator having a thermally insulated compartment, absorption refrigeration apparatus including a plurality of evaporation members one above the other in said compartment, an absorber interconnected with a lower member for circulation of inert auxiliary gas therebetween, a condenser having connections for delivery of liquid refrigerant from a first part of the condenser to said lower evaporation member and from a further portion of the condenser to an upper evaporation member, said evaporation members being located in the upper part of said insulated compartment so that air therein is 55 cooled by natural flow downwardly over first said upper evaporation member and then said lower evaporation member, and means for conducting part of the inert gas from said lower evaporation member to said absorber in a path of flow including said upper evaporation member, whereby said upper evaporation member operates at a temperature higher than that of said lower evaporation member, and air in said compartment is cooled in two stages except at low condenser temperatures 70 75

when liquid flows only from the first part of said condenser to said lower evaporation member, said upper evaporation member having relatively extensive heat transfer surface for adequate protection 5 cooling of the air when the condenser temperature is high enough so that liquid flows from the further part of the condenser to the upper evaporation member.

3. In a refrigerator having a thermally insulated compartment, absorption refrigeration apparatus including a first evaporation member comprising a pipe coil in the upper part of said compartment, a second evaporation member comprising a conduit having relatively extensive heat transfer surface and arranged above said pipe

coil so that air in said compartment is cooled by natural flow downwardly over first said upper evaporation member and then said lower evaporation member, an absorber interconnected with said pipe coil for circulation of inert auxiliary gas therebetween, an air cooled condenser having connections for delivery of liquid to both said evaporation members, and means for conducting part of the inert gas from said pipe coil to said absorber in a path of flow including said upper evaporation member, whereby said upper evaporation member operates at a temperature higher than that of said pipe coil, and air in said compartment is cooled in two stages. 5
